UNITED STATES PATENT OFFICE.

JAY HOWARD GODSHALL, OF OSHKOSH, WISCONSIN, ASSIGNOR TO GODSHALL PAPER
BOX CO., OF OSHKOSH, WISCONSIN, A CORPORATION OF WISCONSIN.

BOX CONSTRUCTION.

Application filed June 26, 1922. Serial No. 570,884.

To all whom it may concern:

Be it known that I, JAY HOWARD GODSHALL, a citizen of the United States, and resident of Oshkosh, in the county of Winnebago and State of Wisconsin, have invented new and useful Improvements in a Box Construction, of which the following is a description, reference being had to the accompanying drawings, which are a part 10 of this specification.

This invention relates to a box construction and more particularly to boxes formed of material such as described in my co-pending application in which the material 15 is a composite board formed of outer layers of wood veneer and an inner layer of paste or paper board.

The invention has for its particular object to provide a box which will be simple 20 in construction, cheap to manufacture and which will furthermore be strong and durable.

The box construction described is adapted particularly to be made of the composite 25 board referred to hereinbefore, but as the description proceeds, it will be apparent that a box in accordance with this invention may be constructed equally as well with other types of material.

The manner of carrying out this invention 30 will be made more apparent in the accompanying specification and drawings.

In the drawings, Fig. 1 is a plan view 35 of the box blank,

Fig. 2 is a fragmentary section taken on the plane indicated by line 2—2 in Fig. 1.

Fig. 3 is a perspective view of the box 40 complete, certain parts being broken away,

Fig. 4 is a fragmentary section taken on the plane indicated by line 4—4 in Fig. 3 45 and

Fig. 5 is a fragmentary section taken on the plane indicated by line 5—5 of Fig. 1.

Referring now more particularly to the 50 drawings wherein like reference characters indicate like parts, it will be noted that the material of which the box is to be formed is first blanked as indicated in Fig. 1, thus providing a bottom 10, sides 11 back 12 and front 13. In order to enable the material 55 to be folded into the box shape, the upper layer of wood is removed along the lines of fold as indicated at 14 and cut along the same line at the opposite side as indicated at 15 (see particularly Fig. 2.) This en-

ables the material to be conveniently folded.

When the sides, back and end portions have been folded up, they are connected together by clips 16 such as illustrated in Fig. 3. The outer corners of the box are 60 then covered with strips of paper or fabric 17 such as is customary in cigar box constructions, it being the particular object of this invention to construct a box for cigars. 65

A cover 18 formed preferably of the same material is hinged to the box in the ordinary manner by means of a strip of fabric 19 or the like pasted respectively along the upper edge of the rear of the box and the rear edge of the cover 18. For securing the 70 cover in closed position a small brad 20 is used.

In order to provide means for securely holding the brad 20, the interposed layer of paper or paste board 21 (see particularly 75 Fig. 5) is cut away to accommodate an insert 22 of wood. This insert is positioned immediately under the brad 20 whereby a solid portion is provided, into which to drive this brad. 80

From the foregoing it will be seen that there is provided a box adapted for cigars or the like which will resemble in every particular cigar boxes made of wood, a composite board material however being substituted. By the manner of construction herein described, the box may be cheaply manufactured without sacrificing in any degree the rigidity and durability necessary to such box construction. 85

While the invention has been described as relating particularly to a cigar box, it will be obvious without further discussion that boxes particularly adapted to contain other articles may be manufactured without in any manner departing from the spirit and scope 90 of this invention.

In a like manner composite board of other types may be employed and the details of construction of the box may be varied within 100 certain limits. To this end reservation is made to make such changes as may come within the purview of the accompanying claims.

Having thus described the invention what 105 is claimed is:

1. A box formed of composite board, the body of said box being formed of a single piece of material folded to form a bottom, ends and back and front portions, the outer 110

layers of said composite board being cut along the lines of fold, and a cover hinged to said box.

2. As an article of manufacture a box 5 formed of multiply composite material, the body of said box being formed of a single piece of material cut and folded to form a bottom, ends and back and front portions, the outer plies of said composite material being removed and cut along the lines of fold, 10 clips for uniting the edges of said box and a cover of similar material hinged to said box.

3. As an article of manufacture a box 15 formed of multiply composite material, the body of said box being formed of a single piece of material cut and folded to form a bottom, ends and back and front portions, the outer plies of said composite material being removed and cut along the lines of 20 fold, clips for uniting the edges of said box, a cover of similar material hinged to said box, and a wood insert in the front portion of said box to accommodate and secure a brad adapted to be driven through said cover 25 and into said insert.

4. The method of forming a box made of composite board which consists in cutting and folding a blank of composite material to 30 form the bottom, ends, back and front portions of the box, removing the outer layer

of said composite board at one side thereof and along the lines of fold and cutting the other outer layer of said composite board on the opposite side thereof and along the lines of fold, removing a section of the interposed 35 layer of said composite board at the front portion of the box, inserting a wood insert in the recess formed thereby, uniting edges of the box by clips and providing a cover to said box hinged thereto by a strip of fabric 40 or the like.

5. As an article of manufacture a box formed of composite board, said box having a body portion formed of a single sheet of material cut and folded to form a bottom, 45 ends and back and front portions, the outer layers of said composite material being cut along the lines of fold to facilitate the bending of the box into shape, metallic clips for uniting the adjacent edges of the ends, back 50 and front portions, a cover formed of composite board, a strip of fabric or the like pasted to said cover and to said box for securing said cover thereto and a wood insert in the front portion of said box adapted to 55 receive and secure a brad passing through said cover and into said wood insert.

In testimony whereof, I affix my signature.

JAY HOWARD GODSHALL.
